UNITED STATES PATENT OFFICE

2,265,535

ELECTRIC MATTRESS

John R. Lubeck, Alameda, Calif.

Application July 10, 1939, Serial No. 283,613

1 Claim. (Cl. 128—376)

This application relates to electro-therapeutic apparatus, and particularly to an applicator constructed in the form of a pad or mattress, and designed to apply gentle current, either alternating or direct, to substantially the entire body of a patient over a relatively long period of time, e. g., throughout the night or at other times when the patient is asleep.

Among the objects of my invention are: To provide an applicator which may be used with a treatment system for giving protracted treatments with a minimum of discomfort; to provide an applicator which will apply gentle current, of which the patient is barely conscious, if at all; to provide an applicator which will apply sufficiently high voltages to a patient's skin to cause an appreciable current flow without involving danger of shock; to provide an applicator wherein the electrodes are permanently arranged in the desired position, without danger of shorting; to provide a treatment system in accordance with the aforementioned objects; and to provide a convenient and economical apparatus for carrying out such treatments.

Other objects of my invention will be apparent or will be specifically pointed out in the description forming a part of this specification, but I do not limit myself to the embodiment of the invention herein described, as various forms may be adopted within the scope of the claim.

I have found, over a long course of experiment, that the electro-therapeutic effect of extremely mild current, either alternating or direct, particularly direct current, continued over long periods of time, are quite different from the effect of the heavier currents more commonly used applied over short periods. The conditions indicating treatments of this character and the results obtained are, per se, no part of this invention. I have found, however, that it is desirable to subject as large a portion of the patient as possible to the effect of these mild currents, both for the therapeutic effect obtained thereby, and to reduce the current density on any one portion of the patient's skin, thus preventing local heating effects or burning. To apply such treatments in a medical office would require undue amounts of time of both the patient and his physician. The ideal time and place for carrying them out is while the patient is sleeping. The broad purpose of this invention, considered apart from the specific objects as enumerated above, is to provide a type of treatment and a method of applying the same which will enable such treatments to be carried out in the patient's own home; the

physician may make such adjustment in the apparatus as he deems fit. The apparatus may be connected to the ordinary power supply in the patient's home, and, when the patient goes to bed, the treatments occur automatically.

Considered in terms of apparatus, my invention comprises a pad or mattress which includes two conductors of extended area which cover the greater part of the surface of the mattress or pad upon which the patient would normally lie, these two conductors being separated at the central portion of the pad at a space of not over a few inches. Covering the entire surface of the pad and both of the conductors is a layer of porous material. I have found wool to be the most satisfactory, and of woolen materials I prefer flannel. This does not, however, exclude the use of other than all wool materials, since fairly successful results have been obtained with part wool blanketing material and even with "flannelette." Closely woven materials of fine spun threads, such as sheeting or ticking, however, are not satisfactory for the purpose. A connection is made to each of the two conductors, and in cases where direct current is available or where the current is desired purely for external effects, these connections can be supplied through a current-limiting resistor direct from the lighting mains. Under ordinary circumstances, however, 20 D. C. of the proper potential is not ordinarily available, and hence it is generally desirable to provide a transformer and rectifier for supplying limited amounts of direct current to the two conductors. In this case it is possible to make the 25 current carrying capacity of a rectifier tube also serve the purpose of the current limiting resistor.

In order to use the apparatus the connection is made to the conductors as above described and the patient lies upon the pad, either directly upon the flannel or similar covering, or else separated from it by no more than a thin sheet. The patient is preferably covered exactly as he normally would be upon retiring. At the start, no current whatever normally flows, and this is, of course, what would normally be expected since both the wool and any sheets used are insulators. After a short period of time, usually of the order of about twenty minutes, a slight current flow may be detected, and the patient experiences a 30 distinct feeling of warmth, but this is all. The current continues to increase for a time, and then ordinarily assumes an approximately steady value which remains substantially constant until the patient changes position.

I attribute these effects to electrolytic con-

duction from the perspiration of the patient's body, diffusing through the loose porous material of the cover of the conductors. It is for this reason that tightly woven material such as sheeting or ticking is not satisfactory. With such material, if the patient lies in one position, one point will become definitely moist and will carry more than the desirable amount of current, which causes heating or even actual discomfort. This causes further perspiration at this one point, and the effect is cumulative. With wool, however, the moisture diffuses throughout the pores of the material, and unless excessive sweating takes place the current density over any area of the patient's body is self-limiting. This current diffusion occurs even though a thin sheet be placed over the wool, though I prefer not to do this unless the patient has an extremely sensitive skin which is irritated by contact with wool. The matter can be stated crudely by saying that the cotton sheeting acts as if it were either a complete conductor or a complete non-conductor, whereas the perspiration supplied by the patient and acting as an electrolyte so diffuses through the wool, even though the latter be covered by cotton, so as to distribute the current supplied.

The actual method and means for applying the invention can best be understood by reference to the various figures of the drawing, wherein:

Fig. 1 is a plan view of a pad embodying my invention and designed for use over the customary mattress.

Fig. 2 is a fragmentary sectional view of a portion of the pad of Fig. 1.

Fig. 3 is a preferred form of the device, shown in longitudinal section, and including a schematic showing of a rectifier circuit for supplying treatment current.

Considering the figures now in detail, the two conductors 1 and 3 are preferably loosely woven screen of very fine wire. No. 10 mesh screen formed of No. 36 bare copper wire is satisfactory, although the actual mesh, size of wire, and even of material are not important.

Covering both sides of the screen forming the conductors is a bag or double layer 5 of blankets, which may be all or part cotton as has been indicated above, but is preferably wool. The blanket material is sewn around the edges and is preferably quilted as shown by the stitching 7 to prevent shifting of the conductors. A connection cord 9, provided with a plug 11, is connected to the two conductors. The size of the applicator is made so that it will cover substantially the whole top of a standard size mattress—single, double, or three-quarters as the case may be—and the patient lies upon the pad either directly or upon a sheet placed over the pad. Ordinary covers are used over the patient. The plug 11 connects to an ordinary lighting service, and the maximum current which can flow is limited by a resistor 13 included in the cord 9. This resistor is ordinarily of such value as to limit the current to a few milliamperes at most, even should a dead short be applied across the conductors 1 and 3.

Figure 3 illustrates a form of the invention wherein the device is embodied in a thicker pad or mattress, this being a preferable form, although it is of course, more elaborate and hence more expensive than the pad first described. The body 15 of the mattress is composed of any of the ordinary mattress materials—curled hair,

cotton linters, excelsior or any of the other resilient substances customarily used for this purpose, including, if desired, the so-called "inner-spring" resilient wire fabricated body. The two conductors 17 and 19 are disposed over the surface of the body 15 in substantially the same manner as the conductors in Fig. 1, and comprise bodies of resilient "metal wool." I prefer for this purpose to use a brass wool, compacted of thin ribbons or coils of brass, and without sharp ends. Steel wool, as customarily used, possesses sharp ends which may and almost certainly will penetrate the upper covering of the mattress, and lead to penetrating contact with the skin of the patient which may cause laceration or even serious burns. The two conductors 17 and 19 are separated by a strip 21 of the more usual mattress padding.

The lower cover 23 of the mattress may be ordinary ticking. The upper cover 25 however, is again preferably of flannel or other woolen fabric. The usual tufting 27 is employed to hold the padding in place. For obvious reasons metal buttons should not be employed for locking the tufting. I prefer, also, that the cords or threads 29 used in forming the tufting be of silk, and the same is true of the threads 7 used for the quilting illustrated in Fig. 2.

Contact with the conductors 17 and 19 is preferably made by contact to pieces of screen 31, held in place between the mattress body 15 and the metal wool by means of one of the tuftings in each section of conductors. Any other method of making a contact to the metal wool, which is firmly locked in place may, of course, be used.

In Fig. 3, I also show schematically one method of applying direct current treatment to the patient from an alternating current source. The simple connection shown in Fig. 1 can, of course, only be used to supply current of the same type as is supplied by the mains, and can be connected either to direct or alternating current supplies. With the type of connection shown in Fig. 3, only alternating current can be used.

With this arrangement connection to the A. C. supply is made through a plug 33, which is connected to the primary 35 of a transformer which has two secondary windings. Of these, one is a high tension winding 37, the two ends of which connect to the two plates of a full wave rectifier tube 39. The second secondary winding 41 is a low tension winding for supplying the filament of the tube 39. The two leads 43 and 45, connected to the conductors 17 and 19, are also connected respectively to center taps on the two secondary windings. A resistor 47 may be supplied for controlling the current in the filament of the rectifier tube.

The circuit described is, of course, a simple rectifier circuit such as is frequently used in the radio art. It supplies unidirectional current to the conductors 17 and 19, and if the current be limited by the values of filament current supplied it has the advantage that a relatively high overall voltage may be used applying a fairly high current through to the patient, even in the initial stages of the treatment, and that when conductivity has been increased by the patient's perspiration the current will still be limited. In other words, the use of an electrical discharge tube as current-limiting device has the effect of a variable resistance which is high when the external resistance is low, and low when the external resistance is high.

I claim:

An electrical applicator adapted to receive the body of a patient to be treated, a pair of flexible conducting members disposed on the top of the applicator at each end thereof and positioned in spaced edge to edge relationship, said conducting members being insulated from each other by a section of the applicator consisting of electrical insulation located substantially centrally of the applicator, connecting leads to said conducting

10

members, a cover for the applicator and conducting members comprising a soft loosely woven fabric having a nap-like surface, each of said conducting members including a mesh screen, and a 5 layer of metal wool filling the space between the screen and said cover in a direction normal to the extent of the applicator on one side thereof only.

JOHN R. LUBECK.
